J. E. PAULSON AND C. W. ALMQUIST,

POCKET RULE HOLDER.

APPLICATION FILED JULY 10, 1919.

1,334,394.

Patented Mar. 23, 1920.

FIG. 2.

FIG. 1.

INVENTORS:

John E. Paulson and Carl W. Almquist

BY THEIR ATTORNEY:

A. M. Carlsen.

UNITED STATES PATENT OFFICE.

JOHN E. PAULSON AND CARL W. ALMQVIST, OF MINNEAPOLIS, MINNESOTA.

POCKET-RULE HOLDER.

1,334,394.

Specification of Letters Patent. Patented Mar. 23, 1920.

Application filed July 10, 1919. Serial No. 309,966.

To all whom it may concern:

Be it known that we, JOHN E. PAULSON and CARL W. ALMQVIST, the former a subject of the King of Sweden, the latter a citizen of the United States, residing at Minneapolis, in the county of Hennepin and State of Minnesota, have invented a new and useful Pocket-Rule Holder, of which the following is a specification.

Our invention relates to means for clasping tools so they do not drop out of garment pockets in which they are carried. The device is especially designed for holding a folded rule in the pocket of a coat, apron or other garment worn by a mechanic, so that when he stoops or bends over the rule can not escape from the pocket.

In the accompanying drawing, Figure 1 is an elevation of a portion of a garment having a pocket and our device applied thereto and a rule held in the device; a piece of the garment being broken away to expose the rule and the device within the pocket. Fig. 2 is a section on the line 2—2 in Fig. 1.

Referring to the drawing by reference numerals, 3 designates the garment, of which 4 may be the cloth and 5 the lining if the pocket 6 be an inside pocket, and if 30 it be an outside pocket, then 5 will be the cloth and 4 the lining. In either case 7 is the upper edge of the pocket.

The clasping device for holding the rule 8 in the pocket is formed of a strip of 35 metal bent to a U-shape, 9, having a plain arm 10 and another arm, 11, parallel thereto and having its upper end 12 returned downwardly outside the pocket, thus forming an inverted U-shaped bend, 13, which 40 straddles loosely over the edge of the pocket. The short arm of the bend or staple is provided at its inner side with a few teeth, 14, and thereabove the staple is provided with an aperture 15, in which is inserted to swing 45 the upper end 16 of a spring-bar 17—23, which extends through an aperture 18 in the arm 11. The upper arm, 17, of said spring bar is provided with teeth 19, which 50 coact with the teeth 14 in gripping the edge of the pocket, so as to hold the device in the pocket.

The spring bar 17—23 is near its middle provided with an aperture 20, into which projects a stud 21 on the arm 11. Said stud may have a shoulder 22 serving as a fulcrum or resting point for the spring bar. The lower portion of said bar extends almost diagonally across the space between the two arms 10, 11, forming a spring-arm 23 (see Fig. 2), between which and the arm 10 the rule 8 is clasped and held. To make said spring arm 23 more effective it is reinforced by a compression coil spring 24, which has one end secured to the arm 11 and the other end to an overbent end portion, 25, of the spring arm 23; said portion 25 serving to hold the spring 24 without interfering with the smooth face of the spring arm 23 that is to contact with the rule.

In the use of the device the device is attached to the pocket in the manner shown and described, by pressing the arm 16 toward the garment while the edge of the pocket is admitted between the teeth 14 and 19, and as the arm is then released the said part of the pocket is gripped between the teeth and thus the device is held in the pocket. The rule 8, or any other size and form of rule, according to the size of the 50 device and the pocket, is then pushed downwardly into the device, the spring arm 23 and spring 24 yielding to admit the rule, and then clasping and holding it until it be removed by force.

What we claim is:

1. In a device of the class described, a U-shaped body piece adapted to be carried in a pocket, one arm of the U having at its upper end a clasp adapted to clasp over the 55 edge of the pocket, a spring arm extending from one arm of the U at a slant into the space therein and adapted to pinch a rule or similar tool against the other arm of the U; said spring arm extending through an 60 aperture in one arm of the U and upward at the outer side thereof and forming one of the jaws clasping the edge of the pocket, the other jaw of said clasp being formed of the integral upper end portion of the 65 adjacent arm of the U, the latter portion being bent downward outside the pocket.

2. The structure specified in claim 1; said apertured arm of the **U** having near the aperture a shouldered stud and the spring-bar or arm having an aperture engaged by 5 said stud, whereby sliding movement of the spring bar is prevented; and means at the upper end of the apertured arm of the **U**

for preventing edgewise swinging of the spring-bar.

In testimony whereof we affix our signatures.

JOHN E. PAULSON.
CARL W. ALMQUIST.
